ANIMATED GREETING CARD

Milton D. Youngren, Glencoe, Ill., assignor to
 Hall Brothers, Inc., Kansas City, Mo., a corpora-
 tion of Missouri

Application March 17, 1952, Serial No. 276,915

4 Claims. (Cl. 46—37)

1

This invention relates to improvements in nov-
 elties and more particularly to cards or folders
 for use in extending greetings, making announce-
 ments and other purposes.

The principal object of the invention is to pro-
 vide a new and improved medium, such as a card,
 with parts of a figure representing various char-
 acters movably secured to the face of the card in
 such a manner as to produce the effect of ani-
 mation of the characters, or a gesture or grim-
 ace when moved in the intended manner.

Other objects of the invention are to provide
 a card of this character made from heavy paper,
 cardboard or the like having representations
 mounted thereon and parts of the card being
 adapted to cooperate with each other so as to
 impart relative movement to certain parts of
 the representation; to provide a novel enter-
 taining medium of this character which may be
 applicable for use on various greeting cards, ad-
 vertising matter or the like; and to provide a de-
 vice of this character consisting of a piece of
 paper, cardboard or the like having fold lines,
 so that parts of the card will fold over each other,
 one of the folded parts having a longitudinal
 slot therein and the other part adapted to en-
 gage therein so that the parts may be movable
 toward and away from each other upon com-
 pression of the back of the card, and having con-
 nection with the representations on one of the
 folded portions whereby the representation may
 be animated or moved upon movement of the
 respective folded over sheets.

Still another object of the invention is to pro-
 vide the front of the card with parts of char-
 acters and the tongue or tab underneath thereof
 with parts of the character, the front having
 openings therein whereby the character will
 change expression upon movement of the re-
 spective parts of the card.

In accomplishing these and other objects of
 the invention, I have provided improved details
 of structure the preferred forms of which are il-
 lustrated in the accompanying drawings wherein:

Fig. 1 is a front elevational view of a card em-
 bodying the features of the present invention.

Fig. 2 is a front elevational view of the card
 shown in Fig. 1 showing a different expression
 of the character shown thereon.

Fig. 3 is a fragmentary view particularly illus-
 trating the slot for movement of the movable
 parts.

Fig. 4 is a further fragmentary view showing
 the slots with the movable parts in a different
 position.

2

Referring more in detail to the drawings:

1 designates a device embodying the features
 of my invention comprising a sheet of cardboard
 or the like 2 having fold lines 3 and 4 so that the
 5 cardboard can be folded over forming a back 5,
 a front section 6 having a longitudinal slot 7 near
 its free edge as best illustrated in Figs. 1 and 2.

The cardboard is cut away on each end as in-
 dicated at 8 and 9 (Fig. 1), and the sheet folded
 over the fold line 4 forming a flap or interme-
 diate section 10 adapted to be inserted in the
 15 slot 7 in the front section 6 of the card. The
 front section 6 is slightly narrower than the back
 5, and the flap or intermediate section 10 ex-
 tends along the back portion of the front 6, as il-
 lustrated in Fig. 4, and is also slightly narrower
 than the back 5.

In the form of the invention shown, a char-
 acter such as an animal 92, here shown to be a
 20 cow or the like, is outlined or depicted on the
 front face 6 of the card and has eye openings 93
 (Fig. 2). Slots 94 and 95 are provided in the
 25 front face 6 of the card set at an angle above the
 eye openings 93, the upper portions of the slots
 30 being closer together than the lower portions of
 the slots. It will be noted the slots 94 and 95
 are curved slightly as best illustrated in Figs. 3
 and 4. Slots 96 and 97 are provided in the inter-
 35 mediate flap 10 and are slightly curved as are the
 slots 94 and 95. The slots 96 and 97 in the inter-
 40 mediate portion are so arranged that they will
 move behind the slots 94 and 95 in the face of
 the card 6 when the intermediate portion 10 is
 moved vertically. Tabs 98 and 99 simulating
 45 ears for the animal 92 are provided having en-
 larged portions extending on the outer face 6
 of the card and tapered at the inner end to form
 arms 100 which extend through the openings 94
 and 97, 95 and 96, respectively, of the face 6 and
 50 intermediate portion 10 of the card. The inner
 ends of the arms are provided with outwardly
 extending tabs 101 and 102 to retain the tabs or
 ears 98 and 99 in said slots.

Animation of the animal or character is ac-
 complished by the thumb and finger on the edges
 55 24 and 25 of the card and vertical movement of
 the flap or intermediate section 10 will cause the
 tabs 98 and 99 simulating ears to be removed
 angularly from the eye openings 93 disclosing eyes
 103 and 104 outlined on the front face of the
 intermediate section adjacent the eye openings 93.
 The natural spring of the back 5 of the card will
 cause the card to assume its original position
 60 lowering the tabs 98 and 99 simulating the ears

of the animal over the eye openings and moving the eyes from back of the eye openings.

It will be noted that the back section 5, front section 6, and intermediate section 10 are normally flat and provide interconnected members with the front and intermediate members being reciprocable relative to each other and the back member being adapted to bow outwardly under pressure applied to the connecting edges when the front and intermediate members are moved in one direction of reciprocation. It is also obvious that the tabs 101 and 102 provide stops which cooperate with the exterior portion of the tabs 93 and 99 to retain the animated members, in this illustrated instance the ears of the animal, within the slots 94-95 and 96-97.

It is also obvious that when the back member bows outwardly it opens up a space to accommodate swinging movement of the stops and the free ends of the arms or tongues 100, and also provides an activating force to return the front and intermediate members to their original position.

It will be obvious that in the form of the invention shown here, movement of the card may be either slow or fast, as desired by the operator thereof, the material used having resiliency so that there is a spring action to the back.

While I have here depicted a certain character on the face of the card, it will be obvious that other forms and characters may be depicted and various ways utilized for showing animation thereof without departing from the spirit of my invention.

What I claim and desire to secure by Letters Patent is:

1. An article of the character described comprising a piece of cardboard folded to form a back section, a front section connected along one edge thereof, the front section having a longitudinal slot near its free edge, an additional section connected to and extending along the opposite edge of the back section and extending over the free edge of the front section and downwardly through said slot, the outline of an animal including a head on the front face of the front section provided with spaced openings for the eyes of said animal, said head having spaced slightly curved slots extending at an angle to each other above and outwardly from said openings, ear members having arm portions extending through said slots, said ear members simulating the ears of said animal and lying over the eye openings when the card is in normal position, said additional section having slots of the same contour as said slots in the front face of said card, said arms extending through said slots in the additional section, tongues on the inner ends of said arms for retaining the ear members in said slots, said additional section having an outline of eyes of the animal adjacent said eye openings in the front face of the card whereby squeezing pressure applied to the folded edges of said sections will cause sliding movement of the front and additional sections and the back section to bow outwardly, the additional section moving said arms causing the ears of said animal to be removed from over the eye portions and the outline of the eyes to be visible through said eye openings and whereby release of pressure on the folded edges of said sections will allow said back of the card to return to normal position causing the ears to be lowered over the eye openings.

2. An article of the character described comprising, a piece of cardboard folded to form a

back section, a front section connected along one edge thereof, the front section having a longitudinal slot near its free edge, an additional section connected to and extending along the opposite edge of the back section and extending over the free edge of the front section and downwardly through said slot, the outline of an animal including a head on the front face of the front section provided with spaced openings for the eyes of said animal, said head having spaced slots extending at opposite angles to each other above said openings, the upper ends of said slots terminating on a line substantially centrally of said eye openings and the lower ends of the slots terminating outwardly of and slightly above said eye openings, ear members having arm portions extending through said slots, said ear members simulating the ears of said animal and lying over the eye openings when the card is in normal position, said additional section having slots of the same contour as said slots in the front face of said card, said arms extending through said slots in the additional section, tongues on the inner ends of said arms for retaining the ears in said slots, said additional section having an outline of eyes of the animal adjacent said eye openings in the front face of the card whereby squeezing pressure on the folded edges of said sections will cause sliding movement of the front and additional sections and the back section to bow outwardly causing the ear members of said animal to be removed from over the eye portions and the outline of the eyes to be visible through said eye openings, said back of the card being under tension whereby release of the squeezing pressure will cause the card to assume normal position causing the ear members to be lowered over the eye openings.

3. An animated card including generally rectangular front and back members and an additional member formed of normally flat material, said back member having one side edge connected with a corresponding side edge of the additional member and the opposite side edge connected with a corresponding side edge of the front member, the opposite side edge of the additional member being free and spaced from said side edge connection of the front member when the back member is in normally flat condition, the front member having a part thereof slidingly embracing and guiding the additional member and for retaining the additional and front members in reciprocating contact with each other, said front and additional members each having an aperture with the aperture of the front member offset from the aperture of the additional member substantially in the direction of reciprocation of said front and additional members, the front member having a representation thereon of a figure, an animating member having an exterior portion normally lying substantially flat against the outer face of the front member and representing a normally movable element of said figure, said animated member having a narrower tongue portion extending through both of said apertures and normally lying flat between the front and additional members when the back member is in said normally flat condition but being adapted to pivot within said apertures when the front and additional members are reciprocated to shift said apertures to and from each other for swinging said exterior portion away from the outer face of the front member, and a stop on the tongue lying substantially flat between the additional and back members when

the back member is in said normally flat condition to cooperate with said exterior portion in retaining said animating member, said back member being adapted to bow outwardly for opening up a space to accommodate movement of said stop when a squeezing force is applied to said connected edges for effecting movement of the front and additional members in one direction of reciprocation and to provide an active force for moving the additional and front members in the opposite direction when the back member returns to said normally flat condition upon release of said pressure.

4. An animated card including generally rectangular front and back members and an additional member formed of normally flat material, said back member having one side edge connected with a corresponding side edge of the additional member and the opposite side edge connected with a corresponding side edge of the front member, the opposite side edge of the additional member being free and spaced from said side edge connection of the front member when the back member is in normally flat condition, the front member having a slot extending along said opposite side edge for passing the additional member therethrough and to provide a part slideable between the additional and back members for retaining the additional and front members in reciprocating contact with each other, said front and additional members each having an aperture with the aperture of the front member offset from the aperture of the additional member substantially in the direction of reciprocation of said front and additional members, the front member having a representation thereon of a figure, an animating member having an exterior portion normally lying substantially flat against the outer face of the front member and repre-

senting a normally movable element of said figure, said animated member having a narrower tongue portion extending through both of said apertures and normally lying flat between the front and additional members when the back member is in said normally flat condition but being adapted to pivot within said apertures when the front and additional members are reciprocated to shift said apertures to and from each other for swinging said exterior portion away from the outer face of the front member, and a stop on the tongue lying substantially flat between the additional and back members when the back member is in said normally flat condition to cooperate with said exterior portion in retaining said animating member, said back member being adapted to bow outwardly for opening up a space to accommodate movement of said stop when a squeezing force is applied to said connected edges for effecting movement of the front and additional members in one direction of reciprocation and to provide an active force for moving the additional and front members in the opposite direction when the back member returns to said normally flat condition upon release of said pressure.
